UNITED STATES PATENT OFFICE.

SAMUEL T. WELLMAN, CHARLES H. WELLMAN, JOHN W. SEAVER, AND THOMAS R. MORGAN, OF CLEVELAND, OHIO, ASSIGNEES TO THE WELLMAN SEAVER ENGINEERING COMPANY, OF CLEVELAND, OHIO, A CORPORATION OF OHIO.

COKE-LOADING APPARATUS.

SPECIFICATION forming part of Letters Patent No. 698,235, dated April 22, 1902.

Application filed March 18, 1901. Serial No. 51,685. (No model.)

To all whom it may concern:

Be it known that we, SAMUEL T. WELLMAN, CHARLES H. WELLMAN, JOHN W. SEAVER, and THOMAS R. MORGAN, citizens of the United States, and residents of Cleveland, Ohio, have invented certain Improvements in Coke-Loading Apparatus, of which the following is a specification.

The object of our invention is to provide means whereby hot coke from a coke-oven or a series of ovens may be quenched and loaded in cars with a minimum expenditure of human labor, the apparatus being also of such character that large quantities of coke can be handled in the shortest possible time and can be delivered into cars on two or more parallel tracks instead of the delivery being limited to a single line of cars, as in other coke-loading machines with which we are familiar.

In the accompanying drawings, Figure 1 represents in side elevation sufficient of a coke-loading plant to illustrate our invention. Fig. 2 is a similar view with some of the parts in a different position. Fig. 3 is an end view 25 of one of the loading-pans and part of the trolley mechanism for handling the same; and Fig. 4 is a view on a reduced scale, showing a modification of part of the invention.

In Fig. 1 of the drawings, 1 represents part 30 of one of a row of coke-ovens, and 2 a cantaliver gauntlet crane, having its legs running upon rails parallel with the row of coke-ovens, this crane spanning two or more railway-tracks, upon which are intended to be run the 35 cars to be filled with the coke. The crane has a traveling trolley 3 for handling any one of a series of pans 4, suitably supported upon walls 5 and 6 in front of the row of ovens, each of these pans serving both as a quenching and loading pan, being open at the inner end or end next the oven, so as to receive the charge of hot coke pushed therefrom and which after being deposited in the pan can be quenched by water directed upon it by means 40 of attendants on the platform in front of the row of ovens, the quenching-water discharging into the channel 7 between the walls 5 and 6, from which it escapes through a suitable drain or sewer pipe. The pans 4 may be of

any suitable length, and the trolley 3 is provided with any desired number of depending hangers, from which the pan may be suspended, there being by preference four of these hangers, one for each corner of the pan, as will be clearly seen by reference to Figs. 1 and 3. For convenience we will denominate that end of the pan farthest from the ovens the "front" end and the open end of the pan, which is nearest to the ovens, the "rear" end. The trolley 3 is preferably provided with a transversely-rigid depending hanger 9 for each of the rear corners of the pan, as shown in Fig. 3, this hanger having at its lower end a hook 10 for engagement with a hook, eye, loop, or equivalent structure 11 at said rear corner of the pan. A locking-bolt 12, controlled in its movement by a solenoid or other electromagnet 13 on the hanger 9, engages with the eye or other attachment on the pan after the same has been caught by the hook and prevents any accidental disengagement of the two, as shown clearly in Fig. 2, where the bolt is in its lower or locking position, as it closes the open side of the hook and prevents the same from being disengaged from the eye on the pan. The eyes or other lifting attachments 14 at the front corners of the pan are engaged by swinging hooks 15, carried by suitable hoisting-tackle 23, depending from a hoisting-drum 16 on the trolley 3, as shown in Figs. 1 and 2. The depending portions of the hoisting-tackle are inclosed in a telescopic incasement 17, the lower section of which is provided with fulcrum-bearings for the swinging hook, as shown, and to which the hoisting-tackle is attached, by which construction said hoisting-tackle is protected from being injured by the steam and hot gases arising from the coke and at the same time is held in a rigid vertical position, so that no swinging or sway- 45 ing of the loaded pan is possible after the same has been picked up by the trolley, thus providing transversely-rigid hangers and lifting devices, to which the pan is suspended at its four corners. A solenoid or other elec- 50 tromagnet 19 on the telescopic incasement of the hoisting-tackle serves to hold each hook 15 in proper engagement with the connection

- 14 at the front corner of the pan and prevents any accidental release of these connections, the bar or rod of such solenoid extending directly into contact with a projecting portion of the hook 15, thus holding the same in positive engagement with the eye on the pan when the solenoid is energized in the manner well understood by those skilled in the art.
- 10 It will be understood that the crane is provided with the usual electric or other motive power apparatus for moving the same, for traversing the trolley, and for operating the hoisting mechanism, such motive power apparatus, as well as the electromagnets 13 and 19, being under control of an attendant in the cab 20 of the crane.

The operation of the apparatus is as follows: The pan resting upon its supports in 20 the inclined position, as shown in Fig. 1, is loaded with hot coke, pushed into the same from the ovens, and after said coke has been properly quenched the crane is moved into line with the pan and the trolley 3 is run forward on the crane until its hooks 10 and 15 have engaged with their corresponding fastenings on the pan, whereupon the connections are locked, as shown in Fig. 2, by means of the magnetic devices described, and 25 the front end of the pan is then lifted by operating the hoisting mechanism of the trolley until the pan has been raised clear of its fixed supports and assumes a substantially horizontal position. The crane and its trolley are then operated until the rear end of the 30 pan occupies the proper relation to a car into which the contents of the pan is to be loaded, whereupon there is a further lift of the front end of the pan, so as to tilt the same and cause its contents to be discharged into the 35 car, as shown by dotted lines in Fig. 2, after which the operations are reversed and the pan is restored to its position on the fixed supports 5 and 6 preparatory to receiving another load. As the entire handling of both 40 the loaded and empty pans is thus effected by a single attendant, the amount of human labor employed is reduced to a minimum, while the use of a number of independent 45 pans for each handling apparatus and the provision for loading cars upon two or more tracks insures the expeditious handling of 50 large masses of coke in the least possible time, and consequently reduces the expense of 55 loading to the lowest possible figure.

In Fig. 4 we have illustrated a modified embodiment of our invention in which a trolley-carrying bridge 21 travels upon runways on elevated supports 22 and 23, one of said elevated supports running along the end of the 60 row of ovens 1 and the other being outside of the tracks which receive the cars to be loaded.

If desired, hoisting-tackle may be employed for the rear portion of the pan as well 65 as for the front portion of the same; but the

use of a rigid support for said rear portion of the pan is preferred because of its greater simplicity and convenience.

Having thus described our invention, we claim and desire to secure by Letters Patent—

1. The combination with a crane structure, of a trolley adapted to run thereon, depending and transversely-rigid lifting and supporting devices carried by said trolley, a loading-pan, and supports to hold the pan in position under the crane structure, so that it can be engaged and lifted by the supporting and lifting devices, substantially as described. 80

2. The combination of a traveling crane, a trolley thereon having transversely-rigid depending supporting and lifting devices, a loading-pan, supporting means for fixedly supporting the pan in an inclined position 85 under the lifting devices, said lifting devices adapted to lift the pan from its support and tilt it so as to dump its contents, substantially as described.

3. The combination of a crane with a trolley having transversely-rigid depending hangers provided with means for engaging a pan, and means for operating one set of said hangers so as to raise the pan from its support, substantially as specified. 95

4. The combination of a crane with a trolley having transversely-rigid depending hangers provided with means for engaging a pan, and means for operating one set of said hangers so as to raise the pan from its support, 100 and then tilt the same, substantially as specified.

5. The combination of a traveling crane with a trolley having depending hangers provided with means for engaging a pan, and 105 electrically-controlled locking devices for said engaging means, substantially as specified.

6. The combination of a traveling crane, with a trolley having depending hangers for engaging a pan, the hangers for one end of 110 the pan being rigid and those for the other end capable of being raised and lowered, substantially as specified.

7. The combination of a traveling crane, with a trolley having depending hangers for 115 engaging a pan, one set of said hangers being rigid and the other comprising hoisting-tackle with telescopic incasement, substantially as specified.

In testimony whereof we have signed our names to this specification in the presence of two subscribing witnesses.
